No. 3259.

PATENTED
NOV 17 1868

W. C. Egleston
Joseph H. Egleston
Concord, N.H.

LEONARD EGLESTON, OF SENECA FALLS, NEW YORK, ASSIGNOR
TO RUMSEY AND CO., OF THE SAME PLACE.

Design No. 3,259, dated November 17, 1868.

DESIGN FOR A STEAM-BOILER PUMP.

The Schedule referred to in these Letters Patent and making part of the same.

To all whom it may concern:

Be it known that I, LEONARD EGLESTON, of the village of Seneca Falls, in the county of Seneca, and State of New York, have invented or produced a new and original Design for the Column and Base, also Bottom Projection or Support at the Lower End of Steam-Boiler Pump; and I do hereby declare that the following is a full and exact description of the same.

The column and base are cast solid, or in one piece, from iron or other suitable metal, and, except the peculiarity of my design, in the usual form.

The peculiar form of the column and base, also projection at the lower end of the pump, and the sections into which it is apparently divided, and the form and continuations of those sections, constitute the design which I claim as my original invention, as shown in the

accompanying drawing, forming a part of this specification, to which reference is made.

Figure 1 is the design for a steam-boiler pump, of which the portion A A represents the column, B B, the base, C C, the projection which rests on the base which supports the pump on the down-stroke of the piston or plunger.

What I claim as new, and my original design and invention, is—

The design for a steam-boiler pump, as shown and described.

LEONARD EGLESTON. [L. S.]
